GAS LASER

Carl J. Clement, 3726 Carlson Circle,
Palo Alto, Calif. 94306

Filed Aug. 28, 1967, Ser. No. 8,404

Term of patent 14 years

(Cl. D26—14)

FIGURE 1 is a right side, top and rear perspective view of a gas laser, showing my new design;

FIGURE 2 is a left side, top and front perspective view;

FIGURE 3 is an enlarged fragmentary left side, top and rear perspective view;

FIGURE 4 is an enlarged fragmentary left side, top and front perspective view;

FIGURE 5 is a side elevational view, the two sides being substantially identical in appearance;

FIGURE 6 is a bottom plane view;

FIGURE 7 is a top plane view;

FIGURE 8 is a rear elevational view, and

FIGURE 9 is a front elevational view.

The dominant features of my new design are shown in solid lines in the drawing.

I claim:

The ornamental design for a gas laser, as shown and described.
